(57) **CLAIM**

The ornamental design for a terminal box, as shown and described.

DESCRIPTION

FIG. 1 is a front elevational view of a terminal box showing my new design;

FIG. 2 is a rear elevational view thereof;

FIG. 3 is a top plan view thereof;

FIG. 4 is bottom plan view thereof;

FIG. 5 is a right side elevational view thereof;

FIG. 6 is a left side elevational view thereof; and,

FIG. 7 is perspective view thereof.

That portion of the claim shown in broken lines form no part of the claimed design.

The word SIEMENS forming a part of the claimed design is a registered trademark of the Siemens AG, the assignee herein.
